UNITED STATES PATENT OFFICE

ERIC O. GOUDEAU, OF DETROIT, MICHIGAN

HOLDING SUPPORT FOR BABY SWINGS

Application filed October 20, 1928. Serial No. 313,829.

The present invention relates to supports for baby swings and has for its principal object to provide a device of this character composed of a plurality of folding legs with 5 each of said legs pivotally attached to the edges of a circular block positioned above the swing whereby to arrange the support substantially in the form of a tripod.

A further and important object of the invention is to provide means engageable with the upper end of the legs for limiting the outward swinging movement thereof and locking means for the leg sections whereby to secure the same in supporting position and 15 against accidental folding movement.

A further important object of the invention is to provide a novel structure for pivotally attaching the upper ends of the legs to the block at the top of the tripod.

20 Other objects and advantages reside in the special construction, combination and arrangement of the various elements forming the invention as more fully hereinafter described and claimed, reference being had to the accompanying drawings forming part hereof wherein like reference characters refer to like parts throughout, and in which:

Figure 1 is a view in elevation of the device shown in swing supporting position.

30 Figure 2 is a similar view showing the same in folded position.

Figure 3 is a plan view of the center block at the top of the tripod and illustrating the bracket sections provided for pivotally connecting the upper ends of the legs thereto.

Figure 4 is a transverse sectional view taken substantially upon the line 4-4 of Figure 3.

40 Figure 5 is a side elevational view of one of the legs illustrating the locking plate for the sections thereof, and

Figure 6 is a perspective view of one of said locking plates.

45 In the drawings wherein for the purpose of illustration I have disclosed a preferred embodiment of my invention, the numeral 5 designates a center block of circular formation with its axis disposed vertically to the periphery of which is secured a series of attaching brackets 6. Each of the brackets 6

are preferably constructed of strap iron with their intermediate portions curved in an arc conforming with the contour of the periphery of the block as shown at 7 and secured to the edges of the block by screws 8 or 55 the like.

The brackets 6 are preferably arranged three in number with their end portions 9 extending radially from the edges of the block at angles of one hundred twenty degrees. 30 The adjacent end portions or arms 9 are disposed in spaced parallel relation, as clearly illustrated in Figure 3 of the drawings, and adapted to receive therebetween, adjacent their outer ends, a leg attaching plate 10 pivotally carried between the arms by a pin 11 extending transversely thereof. The attaching plate 10 is inserted in the bifurcated ends of the upper leg section 12 having a lower leg section 13 hingedly attached thereto by 70 a hinge 14 disposed along the inner edge of the leg section. It will thus be apparent that the lower leg section 13 is adapted to swing inwardly and upwardly with respect to the upper leg sections, when arranging the same 75 in folded position.

Stop pins 15 are also inserted between the adjacent arms 9 for engaging the upper inner edge of the attaching plate 10 of the respective legs whereby to limit the outward 80 swinging movement of the lower ends of the leg. A locking plate 16 is also arranged at the hinged end of the leg sections, said plate being provided with a longitudinally extending slotted openings 17, and a slotted recess 85 18 at one end thereof, a pin 19 extending outwardly from the upper leg section 12 is inserted through the slotted opening 17 whereby to permit the longitudinal sliding movement of the plate into and out of overlapping relation with respect to the hinged edges of the leg sections. A pin 20 also extends outwardly from the edge of the lower leg sections 13 for insertion in the recess 18 at the end of the plate when the same is moved downwardly in overlapping relation 90 with respect to the leg section. Heads 22 formed on the ends prevent withdrawal of the pins from the openings in the plate, and thus serve to secure the same in position on 100

the legs for securing the sections thereof in extended position as clearly illustrated in Figure 4 of the drawings. The structure thus described constitutes a tripod the locking plate 16 serving to prevent accidental folding movement of the legs after the same have been moved to extended position. A bolt 23 extends vertically through the center block 5 with an eye 24 formed at its lower end to which is attached one end of an expansion spring 25 having a cross arm 26 secured at its opposite end and to which cross arm is attached chains 27 for supporting a swing 28 in position at the center of the tripod.

It will be apparent from the foregoing that the structure is admirably adapted for supporting a baby swing without danger of collapsing or tilting over with consequent injury to the child and may be easily and quickly arranged in folded position for the convenient transportation thereof.

When folded, the legs may be secured in folded position by a strap 27 extended thereabout as clearly illustrated in Figure 2 of the drawings.

It is obvious that my invention is susceptible to various changes and modifications in construction without departing from the spirit of the invention or the scope of the appended claim, and I accordingly claim all such forms of the device to which I am entitled.

Having thus described the invention, what I claim as new and desire to secure by Letters Patent is:—

A tripod of the class described comprising a circular supporting block, a plurality of brackets each being provided with an intermediate arcuate portion conforming to the curvature of the block and secured circumferentially to the edge thereof, said brackets having their ends projected radially from the block and in spaced parallel relation to the projected ends of the adjoining bracket, pins connecting the spaced ends of each pair of brackets, legs having one end inserted between the spaced ends of each pair of the brackets and pivotally mounted on said pins and stop pins also connecting the spaced ends of each pair of brackets and engaging the inner edges of the legs to limit outward swinging movement of the free end thereof, said connecting pins and said stop pins combining to secure the ends of the brackets in uniformly spaced relation.

In testimony whereof I affix my signature.
ERIC O. GOUDEAU.
